3 Claims. (Cl. 230—101)

The present invention relates to high speed vacuum pumps used in lamp evacuating machines and the like.

Many vacuum lamp exhaust machines of the rotary indexing type use mercury diffusion pumps to attain the low ultimate pressure required. A typical machine may contain 16 stationary positions connected to various mechanical pumps and 16 rotating pumping units which move with an intermittent motion from one stationary position to the next. Each pumping unit consists of a lamp, connecting head, and mercury diffusion pump. The first two stations on a typical machine of 16 stations are used for rough pumping. Here the pumping unit is evacuated to a pressure below the forepressure tolerance of the diffusion pump. The remaining 14 stations are connected to a backing manifold in which the pressure will never rise above the forepressure tolerance. At these stations the diffusion pump continues to pump on the lamp independently of pressure changes in the backing manifold.

It is imperative that the pressure in the pumping unit is reduced as rapidly as possible at the roughing station. The higher the forepressure tolerance of the pump the less time will be required at the roughing station. A high forepressure tolerance necessitates a small cross-section of the diffuser throat. This same small cross section unfortunately presents an impedance at the roughing stations.

It is therefore the object of this invention to provide a pumping technique which meets these conflicting requirements of high forepressure tolerance and ease of roughing.

The invention comprises an improved pump utilizing this technique.

Referring now to the single figure of the drawing, there is shown a preferred embodiment of the improved pump of the invention as utilized in a conventional lamp evacuating machine.

Background

The lamp machine comprises several pumps 10, each pump consisting of a mercury ejector pump body 12 and a foreline 14. A condensation trap 16 is included in the foreline. These assemblies are mounted on a turntable which moves past several fixed stations A, B, C, D, E, et seq. Stations B, C and D are indicated in the drawing.

A first group of the fixed stations is connected to a high speed mechanical roughing pump. A second group of fixed stations is connected to mechanical backing pumps. As the turntable rotates the pumps 10 past the first group of stations, a lamp bulb 18, which is to be evacuated, is secured to the inlet of pump 12. The roughing pump evacuates the bulb to a rough vacuum (on the order of less than 10 mm. Hg) via the pump body 12 and pump foreline 14. The rough pumping is accomplished in less than a minute and the turntable then moves to the stations C, D, et seq., which are connected to the backing pump system.

Each pump 10 comprises a heater 20 which continuously heats a pool of mercury 22 in the bottom of the pump. When the pressure in the pump falls sufficiently low, the mercury boils and the vapors emerge from a first stage nozzle 24 and ejector nozzle 26 as pumping jets. These pumping jets further reduce the pressure in the pump to a desired level (on the order of less than 5 microns). The

2

operation of the pump 10 proceeds as it passes one roughing station after another and between stations. When the turntable makes a complete circuit back to the roughing stations, the bulb is sealed, the pump 10 is air released, the bulb is removed and a new bulb is applied for rough pumping.

A typical lamp evacuation system would comprise two roughing stations and fourteen backing pump stations. The turntable would rotate at a constant rate with sixteen lamps being processed at once.

The problem

There is a fundamental mismatch in the upper limit of forepressure tolerance of pumps 10 and the lowest pressures which can be reached on a practical basis with the backing pump system. It is customary to accommodate this mismatch by providing a restriction in the foreline of the vapor vacuum pump. Such a restriction appears as a narrow throat 28 in the foreline 14 of ejector pump 10. This solves the forepressure tolerance problem, but creates a problem in rough pumping speed. The restriction of throat 28 causes failures of the rough pumping system to bring the lamp down to the desired rough vacuum.

The solution

The pump is modified by the addition of a Y-form bypass pipe 30 connecting the mercury reservoir 22 with both sides of the throat 28. During exposure to pressures above the rough vacuum pressure, the mercury level in the reservoir is as indicated at 32 and the mercury level in the Y-form pipe 30 is as indicated at 34. The pipe 30 then serves as a high conductance bypass for rough pumping.

As the pressure is reduced and the mercury boils in the pump and discharges vapors through the restricted jet openings 24 and 26, gas pressure builds up over the reservoir 22 to force its level down to the line indicated by arrows 132. The bypass pipe is sized so that the level of mercury is thereby forced up to the line indicated by dashed lines 134. This cuts off the bypass and the pump is then matched to the rough pumping system via restricted throat 28.

Thus the pump as modified is able to meet the dual requirements of matching forepressure tolerance to backing capabilities and high roughing speeds. This is done without the addition of expensive mechanical valves or seals. The bypass 30 has the further advantage of aiding the return of mercury condensed in foreline 14 back to the reservoir 22.

Another restriction in the foreline is that caused by the ejector nozzle 26, as indicated at 36. This restriction is only a minor difficulty compared to that imposed by throat 28. But restriction 36 can also be bypassed during roughing by suitable arrangement of pipe 30 as shown in the drawing.

While one specific embodiment has been described, it should be understood that several variations are possible. For instance, the connection of the bypass pump to the pump body 12 or foreline 14 can be made at any point which is accessible to the bulb 18 via a high conductance gas path. The principles of the invention could be applied to improve other types of vapor vacuum pumps and the improved pumps can be utilized in many applications, other than lamp evacuating machines, requiring high speeds. It is therefore intended that the above description and accompanying drawing shall be read as illustrative of the invention and not in a limiting sense.

What is claimed is:

1. An improved high speed vapor vacuum pump for lamp evacuating machines and the like, comprising a pump body, heating means for vaporizing a reservoir of dense

working liquid, nozzle means for discharging the vapors as pumping jets, a foreline connected to the body, a restriction in said foreline, passage means in open communication with the upstream and downstream sides of said restriction, said passage means also being in open communication with said reservoir below the liquid level thereof, the passage means being constructed to provide a bypass path around the restriction during non-boiling of the working liquid and provide a liquid seal for said bypass path during boiling of the working liquid.

2. The pump of claim 1 wherein said passage means comprise a Y-form pipe with the upper legs of the Y connected to the upstream and downstream sides of the throat, to provide said bypass path, and the lower leg of the Y being connected to said reservoir to provide the source of liquid for sealing the bypass path during boiling.

3. The pump of claim 1 wherein said pump nozzle means includes an ejector nozzle for discharging a jet

directly into the foreline, the said pump nozzle extending into the foreline to form an annular path and wherein the said restriction bypass path starts from the foreline adjacent the ejector nozzle and whereby the said annular path is also bypassed when said bypass path is open.
